UNITED STATES PATENT OFFICE.

J. L. BURDICK, OF NEW YORK, N. Y.

MACHINERY FOR PAGING BLANK BOOKS.

Specification of Letters Patent No. 10,533, dated February 14, 1854.

To all whom it may concern:

Be it known that I, J. L. BURDICK, of the city, county, and State of New York, have invented certain new and useful Ma-
5 chinery for Paging Blank Books and for other Purposes; and I do hereby declare the following to be a full and clear description of the same.

The nature of my invention consists, first, 10 in the use of a vertical cylinder, arranged in a suitable frame, so as to be adjustable by means of a screw or other device, for the purposes hereinafter set forth, the said cylinder having arranged in its periphery, in 15 rows, a set of type having long shanks, so as to admit of their being drawn out by the paging apparatus for the purpose of taking an impression, and then replaced or returned to admit of room for the succeeding 20 type; second, the use of the type having a long shank for adjusting the same in combination with the type wheel; third, the use of the paging apparatus operated by a treadle, the said paging apparatus being 25 composed of a frame having a center post or rod for vertically operating it by means of the treadle, a rack for operating the inking rollers, a rack for operating the half pinion shaft on which are two cranks for 30 operating the hammers to take an impression of the type, and attached to which rack is a cam for operating also the lever for drawing the type from the cylinder to take the impression from them; also, in combination 35 with the frame or center post, an arm for operating a pawl or escapement for moving the type cylinder forward one type after each impression, and also an arm or rod for operating a lever for presenting 40 the inking rollers to the face of the type; fourth, the use of the inking apparatus composed of a set of distributing inking rollers, and an adjustable set of type inking rollers operated by the paging apparatus, and, 45 fifth, the use of the adjustable book holder. But to describe my invention more particularly I will refer to the accompanying drawings, forming a part of this schedule, the same letters of reference wherever they 50 occur referring to the same parts.

Figure 1 is a perspective view of the machine. Fig. 2 is a back view of the paging apparatus as seen when looking at when the machine is in operation. Fig. 3 is a re-
55 verse or front view of the paging apparatus as represented in Fig. 2. Fig. 4 is a de-

tached view of the double acting hammers and shaft to which their arms are attached, the said shaft showing cog teeth half way around its circumference, and into which 60 the teeth of one of the vertical racks works to operate the hammers. Figs. 5, 6 and 7 are representations of the type holders, having long shanks for entering the cylinder.

Letter A, is the frame of the machine, 65 having a cross bar B, and cross head C, between which is arranged on a vertical screw shaft D, a type cylinder D² which may be made of wood or metal, as may be thought best. This type wheel is made hollow, having an inner case and when made of metal 70 which is the case in my working machines is about two to four inches smaller in diameter, and united to the outer shell of the type cylinder by a flanch or cap plate, or 75 cast all in one, and having arms from the interior of the inner case to a hub, through which the center shaft is secured. Through the sides of this cylinder, in uniform rows, or spirally if considered material, are inserted 80 a series of type holders E, E, &c. These type holders have shanks some four inches long, more or less, which are intended to hold the type firmly while being drawn out or pushed back in the cylinder. 85 The outer end of them have a groove e, e, in which the type (see Fig. 6) are inserted. On the extreme end of the type holder is a pin or tooth f, against which a pawl acts to push the type wheel around one type at each 90 impression taken. Also on the upper side of the outer end of the type holder is an edge g. The use of this raised edge is to allow the type drawer to rest upon it, and as it has a groove in it, at each impression 95 taken the lever operating the type drawer draws or pushes back the type.

Letter F, is the frame of the paging apparatus. On this frame is arranged a vertical sledging frame or rod G. This frame or 100 rod works through a box H, on the frame F, and has its lower end attached to a connecting rod I, secured to the treadle J.

Letter K, is the cap piece of the frame or rod G. At the back edge of it is a rack L, 105 projecting downward through the bed of the frame F, and by means of the rack acting upon a pinion cog wheel M, on the series of distributing inking rollers N, N, &c., cause the ink to be uniformly distributed upon 110 the series of type inking rollers o, o, supported in a frame P, and made to act upon

the upper and lower types in the type holder by means of a lever attached to the frame F, and operated by a rod R, attached to the frame F, and operated by a rod R, attached 5 to the cap plate K, as it is drawn down along with the sliding rod G. On the lower end of the rack L, is a toe, which operates as a cam to work the lever S, for holding the endless tape blotter T, passing over the 10 face of the lower printing hammer.

Letter U, is an arm over which the tape passes, having its lower end permanently secured to the frame F, and against which the tape holder S, presses or binds to hold 15 the tape while the impression of the type is being taken.

Letter V, is a second rack attached to the cap piece K, and projecting downward through the bed of the frame F. This rack 20 works into a shaft or cylinder W, having a series of cog teeth on it, about half way of its circumference. At the opposite end are cut two cranks or eccentrics. On these eccentrics, which are directly opposite to each 25 other, are attached the ends of two short arms X, X. These arms are jointed to two other and longer arms Y, Y, which cross each other, and are held by a center pin Z, passing through them and into the frame F, 30 so as to cause the ends of the two levers Y, Y, to operate toward each other. On the ends of these arms are secured the hammers (a², a²) for taking the impression of the type when drawn out between their faces. On the 35 back of the rack V, is a cam or groove b², into which a claw c², attached to a vertical lever h², secured by a pin j², at its lower end to the port k², of the frame F, works, for the purpose of operating the lever m² (attached 40 to the head of the lever h²) for the purpose of drawing out the type holders and type to take an impression therefrom.

Letter n², is an arm attached to the head of the rod G. The object of this arm is to 45 operate a pawl p², attached to a triangular lever q², having a center pin r², secured to the frame F, and one of its arms secured to a sliding rod s², so that as the sliding rod and frame is carried up (by the reacting 50 springs t² attached to the treadle) the end of the arm n², lifts against the head of the sliding rod s², which causes the pawl p², to be drawn back far enough to take up the pin f, on the end of the type holder, and 55 as the treadle brings the sliding rod and frame down it carries also the slide s², down with it till the pawl p², pushes the type wheel forward one type.

Letters u², are reacting springs for reacting or opening the hammers after an 60 impression of the type has been taken.

Letter v², is a type guide or adjuster, having attached to it a lip w², attached to it

for holding the leaf of the book. This type adjuster is secured to an arm projecting 65 from the frame F, and is arranged in front of the type holder, to the outside of the hammers, so that the type will always be drawn out to a uniform length.

Letter x², is a rod on the cap piece K, 70 projecting downward, for operating a pinion wheel y², on one of the inking rollers arranged in the ink box for delivering ink to the distributors N, &c.

Letter z² is an adjustable table on which 75 the book is placed. This table is made to slide backward and forward in a groove, so as to accommodate books of different sizes.

Letter &² is a clamp groove in the edge of 80 the table for holding the back of the book.

Having now described my invention I will proceed to state what I claim and desire to secure by Letters Patent of the 85 United States.

I do not claim the screw on the shaft for moving the cylinder laterally.

What I claim as my invention is—

1. The type holders substantially as set forth, in combination with the vertical type 90 cylinder, for the purposes specified.

2. I claim the use of the vertical sliding rod or frame, having a rack attached thereto, in combination with the double acting crank shaft, and levers for operating the 95 printing hammers, or substantially the same device for the purposes set forth, and also the combination of the rack with the lever, and rod, for drawing out the type holders, or their equivalent devices substantially as 100 hereinbefore set forth.

3. I also claim the use of the vertical sliding rod or frame, having a rack attached thereto for working the distributing inking 105 rollers, in combination with the tape holding lever or their equivalent devices substantially for the purposes set forth.

4. I also claim the use of the vertical sliding rod or frame having a rod attached thereto, in combination with the lever for 110 operating the type inking rollers or their equivalent devices.

5. I also claim the use of the vertical sliding rod or frame having an arm attached to the lap piece of the frame, in combination 115 with the sliding plate and lever and pawl, or their equivalent devices for the purposes substantially as set forth.

6. I also claim the use of the adjustable table and clamps, for holding the book 120 while paging in combination with the paging apparatus.

J. L. BURDICK.
